WRISTWATCH CASE

Raymond Mamie, Alle, Switzerland, assignor to Louis Lang S. A., Porrentruy (Kanton Bern), Switzerland

Application December 23, 1954, Serial No. 33,663

Claims priority, application Switzerland
September 27, 1954

Term of patent 7 years

(Cl. D42—8)

Fig. 1.

Fig. 2.

Fig. 4.

Fig. 3.

Fig. 1 is a top plan view of a wrist watch case, showing my new design;

Fig. 2 is an end elevational view;

Fig. 3 is a bottom plan view; and

Fig. 4 is a sectional view taken along line 4—4 of Fig. 3.

The characteristic features of my design reside in those portions shown in full lines in the drawing.

I claim:

The ornamental design for a wristwatch case, substantially as shown and described.
